UNITED STATES PATENT OFFICE.

CLARENCE E. LEVAN, OF BERWICK, PENNSYLVANIA.

SPARK-ARRESTER.

1,375,052.

Specification of Letters Patent. Patented Apr. 19, 1921.

Application filed May 14, 1918. Serial No. 234,474.

To all whom it may concern:

Be it known that I, CLARENCE E. LEVAN, a citizen of the United States, residing at Berwick, in the county of Columbia, State 5 of Pennsylvania, have invented certain new and useful Improvements in Spark-Arresters; and I do hereby declare the following to be a full, clear, and exact description of the invention, such as will enable others 10 skilled in the art to which it appertains to make and use the same.

This invention relates to new and useful improvements in spark arresters and particularly to spark arresters for use on the 15 smoke-stacks of railway locomotives.

One object of the present invention is to provide a novel and improved structure of this character capable of being slipped over the stack and by means of which the sparks 20 will be prevented from being scattered along the railway but will be conveyed to a convenient receptacle on the locomotive.

Another object is to provide a novel and improved means whereby the arresting device 25 collects the sparks in an annular gutter around the stack and inclined to its axis, whereby they are delivered constantly from the gutter rather than permitted to accumulate therein.

30 Other objects and advantages will be apparent from the following description when taken in connection with the accompanying drawing.

In the drawing:

35 Figure 1 is a side elevation of a locomotive stack and a portion of the locomotive, showing the arresting device mounted on the stack.

Fig. 2 is a top plan view of the same.

40 Fig. 3 is a vertical sectional view taken on the line 3-3 of Fig. 2.

Fig. 4 is a horizontal sectional view taken on the line 4-4 of Fig. 2.

45 Referring particularly to the accompanying drawing, 10 represents the stack of the locomotive 11, in connection with which my invention is used.

Adapted to be slipped onto the upper portion 50 of the stack is a cylindrical sleeve 12, and carried by this sleeve are arms 13 which extend first straight upward alongside the stack and are then deflected and carried inward for a short distance over its mouth, as

clearly shown in the drawing, and connected to the upper ends of these arms is a ring 13' 55 carrying an inverted conical screen 14, the apex of which is directed downwardly into and along the axis of the stack, and spaced therefrom, to permit the sparks from the stack to pass upwardly and outwardly 60 against the outer face of said screen. The base or larger end of the cone 14 rises above said ring and is rolled outwardly as best seen in Fig. 2, and then carried downward in a cylindrical extension or skirt inclosing and 65 spaced some distance from the stack. Secured to the lower portion or skirt of the screen is a metal gutter 15 which encircles the stack and has a spout 16 which connects with a conveying pipe 17, leading to a receptacle 18, mounted on the locomotive. It will be noted that the inner edge of the gutter is connected to the sleeve, while the outer wall is connected to the skirt of the screen, and the bottom is curved transversely. The 70 gutter as a whole is an annular element surrounding the stack and receiving sparks from the screen but it lies in a plane inclined slightly to the axis of the stack and with its 75 delivery spout 16 at the lowest point. 80

By this construction there is the least resistance to the discharge of smoke and sparks from the spout. The smoke may pass straight upward, as there is nothing above the mouth of the stack to resist its passage. 85 The sparks flow upward and diverge along the walls of the inverted cone, pass its base and travel around within the curve or roll (and those which can pass through the screen will here do so), and then pass down within 90 the skirt and drop into the imperforate gutter 15, wherein they automatically travel around the stack and out the delivery spout 16. 95

What is claimed is:

In a spark arrester for smoke stacks, the combination with a screen element including an inverted cone whose apex stands within the stack at its axis and whose walls pass through the mouth of the stack and out of 100 contact therewith, being rolled outward and downward into an encircling skirt; of a sleeve around the stack, arms rising therefrom and bent inward over the upper end of the stack; a ring carried by the upper 105 ends of said arms for supporting said screen

element, and an imperforate annular gutter whose inner edge incloses the stack and whose outer edge is connected with said skirt, the bottom of the gutter being curved

5 transversely and standing oblique to the axis of the stack and cone and having a delivery opening at its lowest point.

In testimony whereof, I affix my signature, in the presence of two witnesses.

CLARENCE E. LEVAN.
